BLUEPRINT REELING DEVICE

Oddous R. Barber, Lynn, and James J. McSweeney, Roxbury, Mass.

Application May 8, 1945, Serial No. 592,624

1 Claim. (Cl. 242—55)

(Granted under the act of March 3, 1883, as amended April 30, 1928; 370 O. G. 757)

1

This invention relates to machines for processing continuous sheets of material. More particularly, it relates to a reeling device for collecting blueprints from a continuous process blueprint machine.

The continuous process type of blueprint machine employs a roll of coated paper. Unexposed paper from the roll is fed into the machine in an unbroken sheet and is not cut into sections before being printed and processed. The roll is attached at one end of the machine, and the paper, as it comes from the roll, is passed under a battery of lights, through processing liquids, and over drying rolls. The processed paper is delivered at a fairly high speed at one end of the machine in a single continuous sheet.

The usual type of machine in use prior to this invention utilizes a series of moving belts to collect the finished sheet of processed and dried paper. The sheet is fed between the belts and is wound by them into a rough roll. This roll is bulky and loosely wound and is difficult to handle. In addition, the constant presence of an attendant is required to prevent the roll becoming fouled or snagged in the belts.

Moreover, the rolls formed by the belts have no smooth inner hole. The edge of the inner end of the paper upon which a roll is formed is rough and jagged and tends to fill up the central portion of the roll. As a result, when a roll is removed from the machine, it is difficult to handle. It is common practice to mount a roll upon a rod of circular cross-section for ease in unrolling prints from the roll and otherwise handling the completed prints. When the roll has no smooth center hole, it is difficult to force the rod through the center of the roll. In addition, the inner convolutions of the roll may be pushed out of shape by the rod and some of the prints on the inner portion of the roll may be injured.

It is an object of this invention to provide an efficient device for collecting a finished continuous sheet of material from a processing machine.

It is a further object of this invention to provide a reeling device for collecting finished continuous sheet material in a compact, tightly wound, neat roll which can be easily handled.

This invention provides, in conjunction with a machine for processing a continuous sheet of material, a device for collecting the sheet which device comprises a rod upon which the sheet is wound, means for supporting the rod so that it can rotate, a means for attaching the sheet to the rod, and a means for rotating the rod in such a

2

manner that a continuous tension is maintained on the sheet during the rotation of the rod.

With the above and other objects and features in view, the invention will now be described with reference to the accompanying drawings which illustrate a preferred embodiment of the invention and will be pointed out in the claim.

Fig. 1 is a side elevational view, partly cut away, showing one end of a continuous process blueprint machine with a reeling device installed in accordance with this invention.

Fig. 2 is a fragmentary end elevational view, partly in section, of the machine shown in Fig. 1.

Fig. 3 is an enlarged perspective view, partly broken away, showing details of the supporting means for one end of the reeling device and of the means for attaching paper to the reeling device.

Fig. 4 is an end elevational view, partly cut away, of the reeling device.

With reference to Figs. 1 and 2, the invention is shown associated with a continuous process blueprint machine which includes a framework 1. Mounted on the framework 1 are rollers 2, 3, and 4 which serve to guide the continuous sheet 5 in the usual way. A chain drive 6, driven by a source of power not shown, rotates a sprocket 7 which, in turn, rotates the roller 4 by means of a gear drive 8 as shown in Fig. 1. The sheet 5 of blueprint paper passes over the rollers 2 and 3, which are idle rollers, and then passes over the powered roller 4. In a part of the blueprint machine not shown, the sheet 5 is exposed to light, processed and dried. The processed sheet, after leaving the roller 4, is ready to be removed from the machine.

Before this invention was developed, finished paper was collected between two series of converging moving belts, indicated at 9 and 10 in Fig. 40. 1. The series of belts 9 is driven by the roller 12 and rides around the rollers 11 and 12. The belts 9 serve to hold the sheet of paper 5 against the powered roller 4 and permit the powered roller 4 to drive the sheet. The belts 10 are driven by the roller 12 and ride around the rollers 12 and 13. A chain drive 14 driven by a source of power not shown rotates the roller 12 to drive the belts 9 and 10. The old method was to permit paper, as it came from the roller 4, to be collected between the belts 9 and 10 to form a loose roll as shown by broken lines at 15 in Fig. 1. This method has been found unsatisfactory because the roll formed between the belts 9 and 10 is rough and bulky. Also the space between the belts 9 and 10 rapidly fills with finished paper,

and an attendant must be present at all times to tend the belts and remove rolls of paper. Moreover, the roll formed by the belts tends to move from side to side upon the belts and bounce up and down with irregularities in the belts. As a result, the layers of paper formed on the roll do not lie smoothly one upon the other and the roll formed does not have even smooth sides and is not tightly wound.

This invention provides a reeling device which collects processed paper in the form of a smooth roll which has a uniform well-formed inner hole and in which each convolution of the roll lies smoothly and tightly upon the convolution below it with the ends of all convolutions in the same plane.

Details of the reeling device are shown best in Figs. 3 and 4. The reeling device comprises two supports 16 and 17, which are firmly attached to the sides of the framework 1 and which support a rod 18 on which the sheet is wound, that has a clamp 19 associated therewith for connecting the end of the sheet thereto. The support 16 (Fig. 4) comprises a supporting bracket 20 and three pairs of rollers 23, 24, and 25 (Fig. 1) arranged to form a cradle for the left-hand end (Fig. 4) of the rod 18. The circular rollers 23, 24, and 25 can be ball bearings, roller bearings, or other appropriate bearings which can support rotatably the end of the rod 18 which is of circular cross-section. The bracket 20 is firmly affixed to the left-hand side of the framework 1 of the machine and carries the circular rollers 23, 24, and 25. The support 17 for the right-hand end of the rod 18, like the support 16, comprises a supporting bracket 26, which is firmly affixed to the right-hand side (Fig. 4) of the framework 1, and three circular rollers 27, 28, and 29 which are also arranged to form a cradle to support rotatably the right-hand end of the rod 18.

Finished paper coming from the roller 4 of the blueprint machine is led to the rod 18 and is attached to the rod by means of the clamp 19 (Fig. 3). The clamp 19 may be made of resilient metal or other resilient material and is somewhat longer than the width of the paper 11 but not so long as the rod 18. It is of C-shape cross section in order that it may quickly and easily be fitted around the rod 18 to attach the end of the sheet 5 to the reeling device. It is of slightly less diameter than rod 18 so that it will clamp the paper to the rod. Paper is attached to the rod 18 by means of the C-shape clamp 19 in such a manner that both of the ends of the clamp project beyond the paper as shown in Fig. 4.

The end 30 of the paper is allowed to overlap the rod 18 a considerable extent (Fig. 3) before being clamped thereto. As shown in Fig. 1, the rod 18 is revolved in a clockwise direction by a belt 31 which is passed around it and which is driven by the roller 11. The end 30 of the paper passes between the clamp 19 and the rod 18 and is folded up over the outer surface of the clamp 19 to form a smooth fold along the forward edge of the clamp 19. The rearwardly directed end 30 of the paper, which is jagged and rough, overlaps the upper surface of the sheet and becomes buried inside the roll as the rod 18 rotates. Consequently, the inner hole of the roll is not filled with a rough jagged end.

The belt 31, which serves to drive the reeling device, is made of a smooth-surfaced elastic material such as rubber. Power is supplied to the belt 31 from the roller 11 (Fig. 1) which in turn is driven by the series of belts 9. The surface of

roller 4 frictionally drives the sheet 5 and the belt 9 at the same speed. The belt 9 drives the roller 11 which, in turn, moves the belt 31 at the same speed of travel of the sheet 5 and the belt 31 drives the rod 18. However, due to the fact that as the sheet winds on the rod 18 the forming roll of paper is of greater diameter than rod 18, there is a constant tension on the sheet as it is wound on the roll. However, the sheet will not tear due to the fact that the belt 31 is free to slip relative to roller 11 and rod 18.

It will be noted that the cradles for supporting the rod 18, formed by rollers 23, 24, and 25 at the left-hand end and by rollers 27, 28, and 29 at the right-hand end, are so arranged that gravity tends to hold the rod in the cradles. In addition, the bar 18 is held in place upon supports 16 and 17 by means of the elastic belt 31 and a hook 33 shown in Figs. 3 and 4. The belt 31 is constructed to exert a continuous pull upon the rod 18 and forces the left-hand end of the rod to ride in intimate contact with the circular rollers 23, 24, and 25 (Fig. 1). The hook 33 holds the right-hand end of the rod 18 in place against circular rollers 27, 28, and 29 as shown in Fig. 3.

When it is necessary to remove a roll of paper from the reeling device, the left-hand end of the rod 18 is pulled forward out of its cradle, stretching the elastic belt 31 (Fig. 4), and the belt is then slipped off the end of the rod. The right-hand end of the rod 18 is also similarly removed from its cradle, the hook 33 being first swung out of position. The roll 32 of processed blueprint sheet is removed with the rod 18 and the C-shape clamp 19 all in place. The rod 18 can then be removed from the completed roll leaving the roll supported upon the clamp 19, which forms a permanent core.

The roll 32 can be carried and handled by means of the extending ends of the clamp without the paper in the roll being touched. As already pointed out, it is common practice to mount a roll upon a second rod for ease in unrolling paper from the roll. The clamp 19 is left in the roll 32 until after it has been mounted on the second rod. Thus, the center hole of the roll is held smooth by the clamp while the second rod is being inserted and the inner convolutions of the roll remain smooth and are not pushed out of shape by insertion of the second rod. After the roll has been mounted on the second rod, the clamp can be withdrawn and is ready for use in forming another roll.

The reeling device devised in accordance with this invention operates automatically. The presence of an attendant is required only when a roll is being started or when a completed roll is being removed from the reeling device.

This invention has been described with reference to a machine for making blueprints. However, it can be adapted readily for collecting a sheet of material from other types of processing machines and numerous other applications of this invention will be apparent.

The invention described herein may be manufactured and used by or for the Government of the United States of America for government purposes without the payment of any royalty thereon or therefor.

Having described our invention what we claim as novel and desire to protect by Letters Patent of the United States is:

In a machine for processing a continuous sheet of material, a device for collecting the sheet in a roll comprising a rod, means for rotatably sup-

porting the ends of said rod, said means comprising a plurality of rollers arranged to form a cradle for each end of said rod, said cradle having an opening therein readily permitting movement of the end of said rod into and out of said cradle, 5 said cradle being so arranged that the end of said rod will be maintained in position by the force of gravity, an elastic belt, said elastic belt passing over said rod to provide driving means for said rod, said elastic belt extending oppositely from 10 said opening in said cradle, the elastic force in said elastic belt tending to force the end of said rod into said cradle, a hook, said hook attached to one of said supports for maintaining one end of said rod in its associated cradle, and a clamp 15 for securing said sheet of material to said rod, said clamp having a C-shape cross-section so that it will embrace and grip said rod, said clamp being of such a length as to extend beyond said sheet of material, readily permitting removal of 20 said clamp and said rod from the center of the roll of said sheet of material.
